UNITED STATES PATENT OFFICE.

HENRY H. F. DAVIE, OF RIVERTON, NEW JERSEY.

DESIGN FOR A HORSESHOE-PAD.

SPECIFICATION forming part of Design No. 29,713, dated November 22, 1898.

Application filed November 1, 1898. Serial No. 696,186. Term of patent 3½ years.

To all whom it may concern:

Be it known that I, HENRY H. F. DAVIE, a subject of the Queen of Great Britain, residing at Riverton, in the county of Burlington 5 and State of New Jersey, have invented and produced a new and original Design for a Rubber Pad for Horseshoes, of which the following is a specification, reference being had to the accompanying sheet of drawings.

Figure 1 is a top or plan view next to the horse's hoof. Fig. 2 is a bottom view next to the horseshoe. Fig. 3 is a rear end view, and Fig. 4 is a side elevation.

Similar letters refer to similar parts in the several views.

A is the base of the pad, to the top of which, Fig. 1, is a hollowed frog-holding extension

or projection B, which is downwardly curved or retreated at *a* to the level of the base A. From the bottom, Fig. 2, of the plate A is projected an inwardly and downwardly curved extension C, which gradually retreats to and merges with the base A at *b* and has its inside surface *c* downwardly and outwardly flared and its end curved at *d*. 25

I claim—

The design for a horseshoe-pad, substantially as shown and described.

In testimony whereof I affix my signature in presence of two witnesses.

HENRY H. F. DAVIE.
